DOOR FOR FIRE BOXES OF OIL BURNING
LOCOMOTIVES

Carl F. Gerlinger, Dallas, Oreg.

Application June 23, 1934, Serial No. 732,111

6 Claims. (Cl. 110—175)

The object of my invention is to promote more complete combustion in oil burning locomotives by providing the firebox door with an air admitting inlet adapted to preheat in part and efficiently distribute the air admitted into the firebox.

I have discovered not only that efficient air distribution into the firebox promotes more complete combustion, thus causing steam to be generated more quickly, but, also, that inefficient distribution of the air into the firebox wastes fuel by causing incomplete combustion, increases accumulation of carbon, and increases maintenance cost of the firebox by permitting cold air to strike heated plates, flues, etc.

A further object of my invention is to prevent flame flashes being emitted from the firebox into the cab, or flashes and flares being projected underneath the engine, which are not only annoying but dangerous at night because of their blinding effect.

I attain the above stated objects of my invention by providing the firebox with a door having an anterior chamber, provided with a damper-controlled air inlet at the bottom, and an interior extension into the firebox; by dividing the air passing into the firebox into courses; by pre-heating the air; and by restraining the passage of the air by back walls and baffles so arranged as to divert and distribute the air in relatively proportioned amounts, all resulting in producing efficient combustion. Said results I obtain by the construction hereinafter fully described with reference to the accompanying drawings.

In the drawings:

Fig. 1 is a front elevation showing the door frame of the firebox and the door hinged thereto; the door hinge being arranged to permit the door to be slid into and out of the door frame for the closing and opening of the door, and entirely clearing the opening into the firebox;

Fig. 2 is a central, longitudinal, sectional view showing a portion of the walls of the firebox, the door frame secured thereto, and the door; the latter having an anterior chamber and an annular interior extension into the door frame;

Fig. 3 shows a front elevation of the door frame, and a front view of the annular interior extension of the door looking in from the plane indicated by the line 3—3 of Fig. 2, at the transverse perforated back wall located in the upper part of the annular interior extension of the door;

Fig. 4 is a fragmentary section showing a portion of the door frame and of the door, the section of the latter being taken on a transverse plane indicated by the arrow 4 of Fig. 2;

Fig. 5 is a fragmentary, sectional top view of a wall of the firebox, the door frame secured thereto, and of the firebox door, this view also illustrating the hinging of the door so that it may be slid into and out of the door frame, for closing and opening; the door being shown in full lines in its closed position, and in broken and dotted lines in its slid-out positions, being finally positioned for being swung out of the way on its hinges; and

Fig. 6 is a diagrammatic drawing of the interior of the end of the firebox illustrating the course of the flame after striking the fire wall.

The door frame *a* is secured to the boiler *b* by screws or bolts *c*. The door, which is hinged to the door frame *a*, comprises an anterior chamber *f* carrying the front wall *g* and an annular interior extension *e*. The annular interior chamber *e* of the door is made with two horizontal baffles *h* and *i*, with a pair of notched lugs *k* and *k'* attached to the annular wall at the front, and similar notched lugs *m* attached to the annular wall at the rear. The anterior chamber *f* of the door is made with a transverse plate *n* at the rear, provided with a broad curved slot opening *o* conforming to the shape of the lower half of the annular interior extension *e*. The transverse plate *n* and front wall *g* are connected by a tubular flue or sanding passageway *p* made integral with them. The interior extension *e* and anterior chamber *f* of the door are fastened together by bolts *d* and *d'*, extending from the front wall *g* to the notched lugs *k*. The bottom of the anterior chamber *f* of the door is rectangular in cross-section; it is open and provides the passageway *q* by which the air enters the firebox door. This passageway is fitted with a damper *r* controlled by a handle *r'*.

A door *s* pivoted on the front wall *g* at *s'* normally closes the entrance into the sanding passageway *p* and rests on the curved flange *p'* at the bottom of the opening to the sanding passageway. A transverse plate *t* is carried by the rear end of the interior extension *e*, and is attached to the interior extension by bolts *t'* held in the notched lugs *m*. Bosses or washers *t2* on the bolts *t'* between the plate *t* and lugs *m* hold the plate *t* spaced from the rear end of the interior extension *e*, allowing a passageway *e'* into the firebox around the plate *t*. The plate *t* is made with a number of tapering, or funnel-shaped air-passing perforations *t3* with the smaller end of these perforations directed towards the firebox.

The anterior chamber of the door *f* is made

with a flange f' provided with a pair of lugs u and u' , which, together with a similar pair of lugs v and v' provided on the door frame a support the double hinge on which the chambered door is hung to the door frame. The double hinge consists of the two members w and w' which are pivoted on the lugs u , u' and v , v' , respectively, the members w and w' being pivoted to each other at their outer ends by the pin $w2$. A handle g' 10 is attached to the front face g of the door.

The action of the double hinge in the opening of the door is clearly seen in reference to Fig. 5. The closed door is first pulled straight out in the direction indicated by the arrow and takes the 15 position shown by the broken line. The two members w and w' of the hinge are moved into the positions indicated by the broken lines at $w3$ and $w4$, respectively. When the door is pulled still further forward it takes the position indicated by the dotted line, and the hinge members 20 are moved into the position indicated by x (Fig. 5). The door can now be swung open and the interior extension e will entirely clear the door frame. When the door is closed it is fastened by 25 a pin y in the lug y' , or by some similar means.

Referring now to Fig. 2, the course of the air thru my door into the firebox is indicated by the arrows. The air enters the door thru the passageway q , the damper r being open. A portion 30 of the entering air passes thru the curved slot o past the lower portion of the wall of the interior extension e directly into the firebox. With the door as illustrated approximately 30% of the air entering the passageway q will pass thru the 35 curved slot o . This passage of air performs the additional service of cooling the bottom of the interior extension e .

The other air entering the passageway q passes around the wall of the sanding passageway p to 40 the upper portion of the anterior chamber f and into the upper half of the annular interior extension e . A portion of this air will enter the firebox thru the passageway e' around the plate t ; a portion will pass thru the perforations $t3$ in 45 the plate t ; and the remaining air will be drawn downward past the baffles h and i and under the bottom of the plate t . By the described construction of my door approximately 40% of the air entering the passageway q passes thru the perforations $t3$ in the plate s ; 10% passes around the plate t and e' ; and 20% passes under the plate t . The proportions are of course mere approximations and can be varied by changing the relative proportions of the curved slot o , the size and 50 number of the perforations $t3$, and the width of the passageway e' . The latter is readily adjusted by changing the length of the bosses or washers $t2$ spacing the plate t from the rear of the interior extension e . However, I have found by actual 55 test that the distribution of the air fed into the firebox in accordance with the above percentages produces best results. I make the distance e' between the plate t and interior extension e approximately $\frac{1}{4}$ inch. The area of the slot opening o , I make approximately 31 square inches, as compared to the opening above the transverse plate n which has an area of approximately 70 square inches. The area of the passageway e' is 60 approximately 10 square inches with the spacing as mentioned, and the area of the interior exits of the perforations $t3$ in the plate t as drawn is approximately 41 square inches.

The door s of the sanding passageway p is of 65 course kept tightly closed except when it is de-

sired to sand the flues, in which case the damper r is closed and the door s is opened.

In Fig. 6, z denotes the flash wall, and the arrows indicate the course of the flame after striking the flash wall. This diagram shows how the air admitted thru my chambered door mixes with the flame to promote proper combustion and more efficient heating of the boiler.

In order to eliminate any possibility of cracking in the interior extension of my door due to 10 expansion and contraction caused by heat changes, I provide a slot h' and a slot i' extending across the baffles h and i , respectively, and a similar slot $e2$ in the bottom of the annular interior extension e . 15

I claim:

1. In combination with a locomotive firebox, a chambered door, comprising an anterior chamber provided with a damper controlled air inlet at the bottom, and an interior preheating chamber, a transverse slotted wall between such chambers, said wall being spaced from the top of said chambers and constructed to block communication between said chambers except at their upper portions and thru said slot, and a transverse perforated wall having the lower edge thereof spaced from the bottom of said preheating chamber and being located between the upper portion of said preheating chamber and the firebox, and horizontal staggered baffles in said preheating chamber, located between the top of said transverse slotted wall and the bottom of said transverse, perforated wall, whereby to retard and divide into courses the air passing into the firebox from the upper portion of the preheating chamber under 25 the last mentioned wall, whereby to effect preheating of the air before entering the firebox. 30

2. In combination with a locomotive firebox, a chambered door, comprising an anterior chamber provided with a damper controlled air inlet 40 at the bottom, and an interior preheating chamber, a transverse slotted wall between such members, said wall being spaced from the top of said chambers and constructed to block communication between said chambers except at their upper 45 portions and thru said slot, and a transverse perforated wall having the lower edge thereof spaced from the bottom of said preheating chamber and being located between the upper portion of said preheating chamber and the firebox, the latter 50 wall provided with a perimetrical air passage, and horizontal staggered baffles in said preheating chamber, located between the top of said transverse slotted wall and the bottom of said transverse, perforated wall, whereby to retard and 55 divide into courses the air passing into the firebox from the upper portion of the preheating chamber under the last mentioned wall, whereby to effect preheating of the air before entering the firebox. 60

3. The combination with a firebox of a door frame secured to the wall of the firebox, a chambered door hinged on said door frame, said door having an anterior chamber with a damper-controlled air inlet at the bottom and an interior preheating chamber, a transverse, slotted wall between such chambers, said wall being spaced from the top of said chambers and constructed to block communication between said chambers except at their upper portions and thru said slot, a transverse, perforated preheating wall having the lower edge thereof spaced from the bottom of said preheating chamber and being located between the upper portion of said preheating chamber and the firebox, horizontal, staggered baffles 65 70 75 75

in said preheating chamber, located between the top of said transverse slotted wall and the bottom of said transverse perforated preheating wall, whereby to retard the passage of air from the upper portion of said preheating chamber under said preheating wall and into the firebox.

4. The combination with a firebox of a door frame secured to the wall of the firebox, a chambered door supported on said door frame by a toggle hinge, said door having an anterior chamber with a damper-controlled air inlet at the bottom and an interior preheating chamber, a transverse, slotted wall between such chambers, said wall being spaced from the top of said chambers and constructed to block communication between said chambers except at their upper portions and thru said slot, a transverse, perforated preheating wall having the lower edge thereof spaced from the bottom of said preheating chamber and being located between the upper portion of said preheating chamber and the firebox, horizontal, staggered baffles in said preheating chamber, located between the top of said transverse slotted wall and the bottom of said transverse perforated preheating wall, whereby to retard the passage of air from the upper portion of said preheating chamber under said preheating wall and into the firebox.

30 5. The combination with a firebox of a door frame secured to the wall of the firebox, a chambered door supported on said door frame by a toggle hinge, said door having an anterior chamber with a damper-controlled air inlet at the bottom and an interior preheating chamber, a transverse, slotted wall between such chambers, said wall being spaced from the top of said chambers and constructed to block communication between said chambers except at their upper portions and thru said slot, a transverse, perforated

35

40

preheating wall having the lower edge thereof spaced from the bottom of said preheating chamber and being located between the upper portion of said preheating chamber and the firebox slightly spaced from the side walls of said preheating chamber, horizontal, staggered baffles in said preheating chamber, located between the top of said transverse slotted wall and the bottom of said transverse perforated preheating wall, whereby to retard the passage of air from the upper portion of said preheating chamber under said preheating wall and into the firebox.

6. The combination with a firebox of a door frame secured to the wall of the firebox, a chambered door supported on said door frame by a toggle hinge, said door having an anterior chamber with a damper-controlled air inlet at the bottom and an interior preheating chamber, a transverse, slotted wall between such chambers, said wall being spaced from the top of said chambers and constructed to block communication between said chambers except at their upper portions and thru said slot, a transverse, perforated preheating wall having the lower edge thereof spaced from the bottom of said preheating chamber and being located between the upper portion of said preheating chamber and the firebox slightly spaced from the side walls of said preheating chamber, horizontal, staggered baffles in said preheating chamber, located between the top of said transverse slotted wall and the bottom of said transverse perforated preheating wall, whereby to retard the passage of air from the upper portion of said preheating chamber under said preheating wall and into the firebox, a tubular sanding passageway extending from the outside face of said door thru said intermediate slotted wall, and a cover for said sanding passageway.

CARL F. GERLINGER. 40
